UNITED STATES PATENT OFFICE.

GEORGE A. BURNHAM, OF ESSEX, MASSACHUSETTS.

AUTOMATIC VOLTAGE-REGULATOR SYSTEM.

1,118,632.

Specification of Letters Patent. Patented Nov. 24, 1914.

Application filed August 23, 1909. Serial No. 514,122.

To all whom it may concern:

Be it known that I, GEORGE A. BURNHAM, a citizen of the United States, residing at Essex, in the county of Essex and State of Massachusetts, have invented an Improvement in Automatic Voltage-Regulator Systems, of which the following description, in connection with the accompanying drawings, is a specification, like letters on the drawings representing like parts.

My invention is an improvement in automatic voltage regulator systems for use with alternating current, having for its object the provision of automatic means for regulating the voltage at the bus-bars or at the center of distribution or on one or several of the feeder circuits in accordance with predetermined characteristics. For instance, in large plants it is necessary to have provision for maintaining the pressure at the end of the feeders constant and provision for regulating the feeder circuit as desired for any given load, and for independently regulating a plurality of feeders from the same bus-bars without varying the bus-bar voltage.

Accordingly my present invention consists in providing means for accomplishing these objects automatically.

The more specific objects and advantages 30 of the present invention will be pointed out more at length in the course of the following description of the constructional details and operation, taken in connection with the accompanying illustrative drawings of the preferred embodiments.

In the drawings, I have shown a diagrammatic view of the preferred embodiment of my invention.

The transmitting circuit 1, 2, is connected 40 by a switch 3 with the bus-bars or source of energy 4, 5, which herein represent a single-phase system or any two bus-bars of the standard polyphase systems of distribution, the load or translating devices being conventionally indicated at 6. Inserted in one 45 side of the service wires 1, 2, is a transformer 7, whose low potential or secondary circuit winding 8 is designed to carry the entire current of the circuit, and whose high potential or primary or supply circuit winding 50 is divided into a plurality of parts, preferably two, 9, 10, as shown in this preferred embodiment. The part 9 is connected permanently across the circuit by wires 11, 12, 55 the former being shown as connecting to the wire 1 and the latter to the wire 2, a switch

13 being preferably interposed as shown. The portion 10 of the transformer is connected by conductors 14, 15, to a regulating device 16 of the kind set forth in my application Ser. No. 485,198 filed March 23, 1909, and shown as driven by a motor 19 engaged by a brush 17 which constitutes the terminal of the wire 14, the wire 15 being connected at 18 to the conducting portion of the regulator. Preferably a condenser 20 is connected across the circuit 14, 15, by wires 21, 22, and a resistance or impedance coil 23 is interposed in the wire 15, said wire 15 being also in series with the wire 12. As 70 herein shown the regulator 16 is in the form of a cylinder having a portion 24 of conductive material and a portion 25 of insulating material. A contact-making voltmeter 26 is used to control the brush movement by suitable means, such as magnets 27, 28, said voltmeter being preferably excited by two currents, one derived from a potential transformer 29 across the circuit 1, 2, and the other from a current transformer 80 30 herein shown as in the wire 2, the needle 31 making contact with the points 32 and 33 in accordance with predetermined variations in the exciting current and potential of the voltmeter. The needle 31 is connected by a wire 34 to a source of energy 35 and the contacts 32, 33, by wire 36, 37, to the solenoids 27, 28, which govern the movement of the contact 17 of the regulator 16, the circuit of said solenoids being completed 90 by a wire 38 from the battery or source of energy 35. In practice, let it be supposed that 4, 5, represent a set of bus-bars in a station and that one or more feeder circuits therefrom are to be independently controlled 95 in accordance with my system, the feeder circuit 2 being a typical circuit, it being understood that substantially the same mechanism will be provided in connection with each feeder circuit (which it is desired to 100 regulate in the station) irrespective of the number thereof connected with the said bus-bars. As the load 6 varies, the voltage at 6 will vary, and hence to maintain it uniform I vary the voltage of the transformer 7, 105 which transformer is connected in series with the line. The voltage of the transformer 7 is varied automatically by short-circuiting preferably one portion of the transformer through varying periods of 110 time determined with reference to the variations in the feeder circuit itself.

Referring now more particularly to the details, it will be seen that as the voltmeter is influenced by either a change in voltage or current or both, *i. e.*, by the transformers 29, 30, in the feeder circuit, its needle 31 is correspondingly moved in one direction or the other so as to energize the regulator controlling means 27, 28, and thereby correspondingly vary the periods of interruption of the short circuit in the transformer 7. If the contact 17 of the regulator moves to the right Fig. 1 the duration of the short circuit will be relatively short, whereas if it moves to the left the duration of the short circuit will be relatively long. As the operation of this type of regulator is well understood and as the regulator itself is not herein claimed, it is deemed unnecessary to explain the same further, the application thereof or of an equivalent relay device to the system and in the combination herein explained constituting my invention, whereby the control of the feeder circuit is rendered automatic as distinguished from the hand control heretofore practised.

In the preferred construction the high potential side of the booster transformer 7, or preferably a portion thereof, is short circuited through a resistance or impedance 23, causing a variation in the boosting effect of the high potential side of the booster transformer, the length of time of said short circuiting and hence the extent of said variation being dependent on the position of the brush 17 of the regulator in accordance with the voltmeter which automatically controls said regulator, and as said voltmeter is automatically responsive to changes in the feeder circuit itself, it will be evident that the entire regulation is thereby automatic. The switch 13, preferably not automatic, when thrown in one position, causes the automatic regulating apparatus to boost, and when thrown in the opposition position to buck, the voltage supplied by the generator. A change of potential in the feeder circuit affects the transformer 29 of the voltmeter, and a change in current in the feeder circuit affects the transformer 30 of said voltmeter, so that whenever the feeder circuit varies, the voltmeter automatically closes the controlling circuit for shifting the contact 17 of the regulator 16 either to the right or to the left, thereby decreasing or increasing, as the case may be, the duration of the short circuiting intervals of the circuit of the high potential side of the booster transformer 7. The boosting transformer 7 having a potential winding 9 as primary and a secondary in series with one of the mains, will give a boosting effect according to the ratio of its primary and secondary turns. The section 10 connected through a resistance 23, the rotary cylinder and its brush 17 will raise or lower the voltage of the feeder

circuit in accordance with the load. The amount of boost will depend on the ratio of turns of coils 9 and 8, and by shifting the switch 13 the transformer may be made to buck the main voltage. Now, the section 10 of the transformer if opened or closed at intervals by the compensating regulator will vary the boosting effect. If the secondary 10 be opened the effect on the line voltage is the same as that of an ordinary potential transformer. There will then be induced in the secondary 8 a certain potential depending on the ratio of turns of 9 to 8. If we short-circuit the winding 10 on itself we would have, neglecting winding 8, a one to one transformer with the secondary short-circuited. This means that in winding 10 current will flow 180° displaced from that in winding 9, and neglecting the loss in transformation between 9 and 10, there would be practically no flux in the transformer core. In other words the two flux components would be equal and opposed, and winding 8 would not be cut by any lines of force, thereby resulting in zero potential across the terminals. This is not rigidly true on account of leakage, and in fact a certain potential would be induced in winding 8. Now if a resistance as 23 be included in the short-circuited section 10, as illustrated, there will be a diminution of current in said section, and the ampere turns of winding 10 will be considerably less than those of winding 9, thereby resulting in an effective resultant flux cutting winding 8 and inducing in said winding a potential depending on the flux threading this winding. If contact 17 is shifted by the voltmeter to insulating section 25 of the regulator the circuit of the coil 10 will be opened, resulting in a maximum flux in the core 8 and a maximum potential on coil 8. This may seem contrary to the theory of the ordinary constant potential transformer, but it must be remembered that the amount of current in winding 8 is not a function of that which flows in winding 9, but is determined by the load 6, whereas in a constant potential transformer connected in the usual way the amount of current passing through coil 8 would be related directly to that which is consumed in the primary and directly controlled by it. Therefore, when section 10 is short-circuited, it is clear that the potential across winding 8 will drop. The movement of contact 17 being controlled by the voltmeter 26, the potential across the feeders 1, 2 can be held constant or varied according to predetermined conditions.

I have herein set forth the best explanation of the operation of my apparatus I can present, but I do not desire to be limited to any particular theory of operation. The reactions in a transformer of the kind herein shown where a coil in series with the line

carries the entire load current is very complex, and the factors vary greatly with varying load conditions. The fact remains, however, that in the apparatus I have shown and described the voltage is regulated automatically by the operation of the apparatus and proper regulation is maintained. In practically operating the apparatus I employ a boosting transformer in which the 10 windings 9 and 10 have an equal number of turns, as indicated diagrammatically.

It will be understood that each feeder circuit from the bus-bars 4, 5, is provided with a similar set of automatic controlling apparatus. In other words, my invention provides automatic means to raise or lower the voltage of the individual feeders irrespective of the voltage of the generator circuit or bus-bars, said raising or lowering of the 20 voltage being accomplished by varying the magnetic flux in the regulating transformer of said circuit by causing automatically the periodic variation of the current flowing in the transformer in accordance with the variations in the load. Instead of definitely changing the flux in the transformer by definite predetermined changes in the current flowing through the transformer, as by means of an automatic switch for cutting 25 out sections of the transformer or by means which varies the relative positions of the coils of the transformer so as to vary the leakage factor thereof, I provide means which maintains a continual variation of the 30 two components of the flux and simply changes the length of said variation, to accomplish the desired end. By this means is varied the time element of the make intervals with relation to the time element of 35 the break intervals, whereby the extreme fluctuations are varied by varying the relative duration or time element of said two sets of intervals. One of its most striking 40 advantages may be explained as follows: As 45 the constantly operating regulator (of my type or the Tirrell type, for instance,) necessarily causes a continual extreme fluctuation of the voltage in the transformer because of its rapid succession of short circuiting and 50 open circuiting operations, causing a rise of voltage during one operation and a fall of voltage during the other operation, both said rise and fall being actually greater than theoretically necessary, in order that the 55 mean results shall be correct, extreme sensitiveness is secured. The practical result is that thereby I am enabled to effect the changes in the voltage of the transformer more nearly instantly or simultaneously 60 with the changes in the load than is possible by the means above mentioned. By providing means which keeps up a constant set of extremes of electric fluctuation in the voltage of the transformer, the sluggish action 65 of the magnetic fluctuation is largely com-

pensated or overcome so that changes in the voltage of the transformer may be considered as practically instantaneous. This produces therefore an instantaneous response in the electric current as required in order to maintain the voltage at the end of the 70 feeder line constant with varying loads.

Having described my invention, what I claim as new and desire to secure by Letters Patent is,

1. In an automatic voltage regulator system, a transformer having a winding in series with the line, a potential winding across the line, and a voltage regulating winding automatically put on closed circuit during 75 intervals of varying duration in accordance with changes of line voltage.

2. In an automatic voltage regulator system, a regulating transformer and its load-carrying circuit, and automatic means periodically to vary the primary current in 80 said transformer in accordance with the variations in the load.

3. In an automatic voltage regulator system, a regulating transformer and its load-carrying circuit, means for producing in 85 said transformer a continuous rapid variation of flux, other than that produced by the natural periods of said circuit, said means being responsive to variations of load in said 90 circuit for changing the components of the effective flux.

4. In an automatic voltage regulator system, a regulating transformer and its load-carrying circuit, an auxiliary transformer 100 winding, continuously operating short circuiting means for intermittently varying the current of said winding, and means responsive to the variations in said load for regulating the durations of the variation intervals of the auxiliary winding.

5. In an automatic voltage regulator system, a transformer having a winding in the load carrying circuit, a regulating winding responsive to variations in the electrical conditions of the load circuit, and means for rendering the winding periodically effective through intervals of varying duration.

6. In an automatic voltage regulator system, a regulating transformer having primary and secondary circuits, one circuit containing a load, a potential circuit across the line and impedance means in a third circuit, and short circuiting mechanism acting on 115 said last mentioned circuit for intermittently varying the primary and secondary components of the magnetic flux in the transformer in accordance with the variations of load in the other circuit.

7. In an automatic voltage regulator system, a regulating transformer, one circuit containing a load, a regulating circuit containing impedance, and short circuiting mechanism acting on said last mentioned circuit for intermittently varying its circuit 120 125 130 135

through said impedance in accordance with the variations of load in the other circuit.

8. In an automatic voltage regulating system, the combination of a supply circuit, a load circuit, a regulating transformer comprising a winding in series in the load circuit, a winding connected to the supply circuit, and an auxiliary winding adapted to be intermittently short-circuited to regulate the voltage of the series winding, and means

for controlling the duration of the short-circuiting responsive to the electrical conditions in the load circuit.

In testimony whereof, I have signed my name to this specification, in the presence 15 of two subscribing witnesses.

GEORGE A. BURNHAM.
